UNITED STATES PATENT OFFICE.

WALTER J. BARRON, OF NEW YORK, N. Y., ASSIGNOR TO DENSMORE TYPEWRITER COMPANY,
OF SYRACUSE, NEW YORK, A CORPORATION OF NEW YORK.

TYPE-WRITING MACHINE.

No. 904,171.

Specification of Letters Patent.

Patented Nov. 17, 1908.

Application filed April 18, 1906. Serial No. 312,368.

To all whom it may concern:

Be it known that I, WALTER J. BARRON, citizen of the United States, and resident of the borough of Brooklyn, in the city of New York, in the county of Kings and State of New York, have invented certain new and useful Improvements in Type-Writing Machines, of which the following is a specification.

10 My invention relates to typewriting machines and more particularly to back spacing mechanism therefor.

One object of my invention is to provide a simple and efficient back spacing mechanism 15 by which the carriage may be moved back step-by-step in a direction opposite to that in which it travels during the ordinary operation of the machine.

A further object of my invention is to provide mechanism of the character specified 20 which may be employed to afford a back feed of the carriage one or more letter space distances at a time as may be desired at each operation.

25 A still further object of my invention is to provide means of the character specified which are in the nature of attachments and may be applied to existing forms of typewriting machines without changing the 30 structural features of said machines.

To the above and other ends which will hereinafter appear my invention consists in the features of construction, arrangements of parts and combinations of devices to be hereinafter described and particularly pointed out in the appended claims.

In the accompanying drawings, wherein like reference characters indicate corresponding parts in the various views, Figure 1 is an 40 enlarged fragmentary plan view of a Densmore typewriting machine with the attachments of my invention shown applied thereto. Fig. 2 is a fragmentary front elevation of the upper portion of the same with parts broken 45 away. Figs. 3 and 4 are fragmentary detail views in front elevation and with parts broken away of the back spacing mechanism and parts of the typewriting machine to which the attachments are applied. Fig. 5 50 is a fragmentary detail plan view of the ordinary mechanism of the machine on an enlarged scale. Fig. 6 is a rear elevation of the same. Fig. 7 is an enlarged detail fragmentary front elevation showing 55 a modified form of back spacing mechanism

embodying my invention. Fig. 8 is a like view of the same showing the parts differently disposed. Fig. 9 is a detail transverse sectional view of the parts shown in Figs. 7 and 8, the section being taken on the line ⁶⁰ *x-x* of Fig. 8 and looking in the direction of the arrow at said line. Fig. 10 is a detail perspective view of a pivoted stop forming a part of the structure shown in Figs. 7, 8 and 9. ⁶⁵

In the various views parts have been omitted and parts broken away to better illustrate other features of the construction

I have shown my invention applied to a No. 1 Densmore machine to which the attachments may be readily applied without modifying any of the structural features of that machine, but it should be understood that the invention may be applied to various other styles of typewriting machines. ⁷⁰ ⁷⁵

A top plate 1 of the machine supports a guide rod 2 which is surrounded by sleeves 3 that project inwardly from the forward ends of arms 4 connected to a carriage truck. A feed rack 5 is secured to the arms 4 of the 80 truck and coöperates with a fixed dog or detent 6 and a loose or stepping dog 7. The loose dog is slotted at 8 and headed screws 9 extend through said slots and take into threaded openings in a plate 10 which constitutes a dog rocker. This construction enables the loose dog to receive a longitudinal movement in the direction of the length of the rack 5. A spring 11 bears at its free end 85 against the loose dog and tends to force it towards the right, this spring being pressed around a screw 12 carried by the dog rocker and secured at its opposite ends to a screw 13.

The dog rocker 10 is pivoted on a shoulered screw pivot 14 which connects the dog rocker to a bracket arm 15 fixed to a spindle 16 which is adapted to turn on its vertical axis in a bearing 17 formed in the top plate 1. A stop 18 is adjustably held in its bearing in a lug 19 which projects from the top plate, by a screw 20. A restoring spring 21 is connected at one end to a pin 22 which projects from the top plate and is connected at its opposite end to a bracket arm 23 on the dog rocker. The pressure of the spring 100 105 21 is effective to turn the dog rocker around the vertical axis of its spindle 16 as well as to turn it around its horizontal pivot 14, thus tending normally to maintain the loose dog in the elevated position and to force it 110

into engagement with the feed rack 5. A spring drum 24 is connected to one end of a band 25, the opposite end of the band being connected to the feed rack 5 so that the pressure of the spring drum tends constantly to move the carriage, comprising the truck and a platen frame now to be described, from right to left across the top plate of the machine. A platen frame 26 comprising a front cross bar 27, end bars 28 and a rear cross bar 29, is provided with rearwardly extending bifurcated arms 30 which embrace the sleeves 3 and are received between the arms 4 of the truck. A platen 31 is provided with a shaft 32 which is seated and adapted to slide vertically in bearings 33 in the end bars 28 of the platen frame when the platen is turned to inspect the writing, said bearings being open at the top to permit removal of the platen. The front cross bar 27 of the platen frame has openings 34 and 35 therein. Anti-friction rollers 36 are mounted on screw pivots 37 which extend through the bar 27 in opposite directions and coöperate with the trunnions 38 of the anti-friction rollers. Each of the rollers 36 is contained in an opening 34 in the front cross bar and is received at its tread in a substantially V-shaped groove 39 of a shift rail 40 carried by arms 41 which are actuated by the usual or any suitable means (not shown) to effect a backward and forward movement of the shift rail to change the case position of the platen. During this movement the arms 30 of the platen frame ride back and forth on the sleeves 3, the shift rail being arrested in its forward movement by the arms 41 contacting with screw stops 42 which are received in threaded openings in arms 43 which project through the top plate 1. A pointer 44 is carried by a bracket 45 secured to the shift rail by screws 46, the pointer co-operating with the carriage scale 47 connected by screws 48 to the front bar 27 of the platen frame.

The dog rocker 10 is actuated in the usual manner, a depending link 49 being pivoted thereto at 50 and connected to a universal bar which is actuated at each printing movement of a finger key. During the ordinary printing operation each depression of a finger key causes the free end of the dog rocker to be depressed, thereby moving the dog rocker from the position shown in Fig. 6, releasing the loose dog 7 from the rack and bringing the fixed dog 6 into engagement with the same tooth which was engaged by the dog 7 so that the feed rack and the carriage controlled thereby are not fed at the down stroke of the key. The release of the loose dog in the manner described enables the spring 11 to force it forward, as in Fig. 5, in position to coöperate with the next advancing tooth of the feed rack on the return of the dog rocker. When pressure on the

finger key is released the free end of the dog rocker will move upwardly under the tension of its spring 21 and the loose dog will engage the advancing tooth of the feed rack and the pressure of the carriage spring 79 will overcome the tension of the spring 11, thus feeding the carriage forward a letter space distance and restoring the loose dog to the position shown in Fig. 6. During the reverse or backward movement of the carriage the beveled edge of the loose dog will coöperate with the beveled edges of the teeth on the feed rack and the feed dog 7 will at this time ride freely over the teeth of the feed rack, the dog rocker at this time moving 80 around the axis of the spindle 16 as a center, as indicated in Fig. 5. A carriage release key 51 is connected to a bar 52 which carries forwardly extending bracket arms 53 pivoted on screw pivots 54 to the arms 4 of the truck. A depression of the release key 51 will swing the bar 52 rearwardly about its pivots 54 against a screw stop 55 carried by the dog rocker and will thus force the dog rocker to turn around with the pivot 16, thereby disengaging the loose dog from the feed rack. 85

The construction as thus far described constitutes parts of the No. 1 Densmore machine and further description thereof is deemed unnecessary. 95

A rack or stop member 56 is secured by screws 57 to the shift rail 40 or to arms 41 which support said shift rail. This rack extends substantially throughout the length of the carriage and is provided for coöperation with a stop 58 that is carried by a hand controlled pivoted device or key 59 preferably made of sheet metal with a hook-like finger piece 60 thereon and depending sides 61. This pivoted device is 100 received within the opening 35 in the front bar 27 of the platen frame, as shown in Fig. 1, and is pivoted at one end on a pivot rod 62 which extends across the opening 35 and through the depending side pieces 110 61 of the pivoted device and is secured at its ends to the bar 27. An arm or finger 63 projects from the pivoted device or key 59 and is adapted to coöperate with a cross web or bar 64 of the platen frame, which bar 64 115 divides the left-hand opening 34 from the center opening 35. The finger 63 and the bar 64 act as stops to limit the upward swinging movement of the pivoted device as shown in Fig. 2. Laterally projecting fingers 120 65 are formed on the pivoted device 59 for coöperation with the bar 27 of the platen frame to limit the downward movement of the pivoted device as shown in Fig. 1. The stop 58 hereinbefore referred to is mounted 125 on the rear depending side 61 of the pivoted device 59 and is adapted to slide thereon in the direction of the travel of the carriage. A headed screw 66 extends through a slot 67 in a slidable plate like member or carrier 68 130

from one end of which the stop 58 depends, and said screw limits the sliding movement of the stop on the pivoted device 59. The left-hand end of the carrier 68 is supported 5 on the pivot rod 62, the carrier being cut out at 69 for this purpose. A laterally projecting pin 70 extends from the carrier and a contractile spring 71 is connected at one end to said pin and is connected at its opposite 10 end to a depending ear 72 formed on the pivoted device 59. A spring 73 surrounds the pivot rod 62 and bears at one end against the bottom of the pivoted device and at its opposite end against the cross bar 15 or web 64 of the platen frame, thus tending to maintain the pivoted device, and the stop carried thereby, in the normal position shown in Fig. 2.

From the foregoing description it will be 20 understood that the pull of the spring 71 is exerted to draw the stop 58 to the limit of its movement towards the right on the pivoted device or key 59, as shown in Fig. 2, and that the pin and slot or sliding connection between 25 the stop 58 and its key 59 constitutes a lost motion connection.

In the operation of the mechanism the operator may grasp the hook-like portion 60 of the pivoted device, pressing it down 30 around its pivot 62 from the position shown in Fig. 2 to that indicated in Fig. 3, thereby forcing the nose of the stop or pawl 58 into engagement between two of the teeth on the rack 56. The operator may then exert a 35 pressure on the carriage from left to right. This pressure may be exerted at the termination of the downward movement through the hook-like part 60, so that one hand of the operator may be employed to effect, by one 40 motion, both the pivotal downward movement of the pivoted device to engage the stop members and to move the carriage to the right. Or, if desired, the other hand of the operator may be employed to move the carriage 45 to the right in the usual manner while the pivoted device is maintained depressed with the other hand. The effect of the movement of the carriage towards the right in the manner described is to move the carriage 50 for a limited distance relatively to the stop 58 while the latter is held in engagement with its coöperating rack 56. The parts thus far shown and described are so constructed and arranged that this movement 55 corresponds to a letter space movement of the carriage, although this distance may be varied by changing the extent of motion between the carriage and the stop 58, as will hereinafter more clearly appear. During 60 the movement of the carriage to the right in the manner described, the teeth of the feed rack 5 will deflect the loose dog out of engagement therewith, moving the carrier around the axis of its pivot 16. The extent

of right-hand movement of the carriage is 65 sufficient to move the feed rack 5 the distance between two teeth thereof so that the loose dog will be disengaged from one tooth of the feed rack and will engage the next tooth to the left thereof when the right-hand 70 movement of the carriage is arrested or when the carriage has moved from the position shown in Fig. 3 to that indicated in Fig. 4 and the engagement thus effected will retain the carriage in the position to which it has 75 been moved backwardly. On reference to these figures it will be seen that the printing point on the platen is at the point "35" on the carriage scale before the movement takes place and is at the point "34" on the carriage scale after the movement has been effected. If pressure at this time is withdrawn from the pivoted device, it will be restored by its spring 73 to the normal position, shown in Fig. 2, and the carriage will 80 be arrested at "34" on the carriage scale by reason of the feed dog 7 being again in engagement with the feed rack 5.

From the foregoing description it will be understood that the downward movement of 90 the pawl or stop 58 into engagement with its coöperating rack or stop member 56 has no effect upon the carriage but is merely effective to bring the stop or pawl 58 into co-operation with the rack and that the movement of the carriage from left to right after this engagement takes place is effected by an independent pressure applied to the carriage either through the finger piece 60 or in any desirable manner. After the pawl 100 58 has engaged its coöperating rack 56 and the carriage has been moved relatively thereto a letter space distance to the right, a disengagement of the pawl 58 from the rack will allow the restoring spring 71 to force 105 the pawl 58 to the right and back to its normal position shown in Fig. 2, one letter space distance. The pawl is then in position to afford another letter space movement of the carriage to the right when it is again 110 depressed and the carriage is moved to the right. In this manner the carriage may be stepped backwardly to the right a letter space distance at each depression of the pivoted device 59.

I have shown another and preferred form of my device in Figs. 7, 8, 9 and 10 of the drawings, wherein the parts are the same as those hereinbefore referred to except that the pawl 58^a and carriage may have a relative movement of a plurality of letter space distances, means being provided for controlling at will the extent of this movement to the distance of one or more letter spaces. In the present construction a relative movement of either one or two letter space distances between the pawl 58^a and the carriage 120 may be afforded, although it should be 125

understood that the number of letter space distances which the pawl or stop 58^a and the carriage may move relatively to each other may be varied as desired. The slot 5 74 in the carrier 68 for the stop 58^a is long enough to afford a double letter space movement of the stop, and headed screw 66 passes through the slot and takes into a threaded opening in the side 61 of the 10 pivoted device or key 59. The pivot 62 for said device constitutes a support for the left-hand end of the carrier 68 as in the device previously described and also constitutes a pivot for a stop 75 which has an off-set portion 76 (see Figs. 9 and 10) for coöperation with a shoulder 77 formed on the stop carrier 68. A finger piece or key 78 is carried at the upper end of a rod 79 which extends loosely through an opening in the pivoted 15 device or key 59 and is pivoted at its lower end to a screw pivot 80 which projects laterally from the stop 75. A spring 81 surrounds the pivot rod 62 and bears at one end against the cross bar 64 and at its other end 20 against the under side of the stop 75, thus tending to force the free end of the stop upwardly to the position shown in Fig. 8 where it is adapted to co-act with the shoulder 77 on the carrier of the stop 58^a. 25 30 and limit the movement of the stop towards the left. The carrier for the stop 58^a is connected to a spring 71 as in the construction heretofore described. Should the operator desire merely to secure a single letter space 35 movement at each depression of the pivoted device 59, it is merely necessary to actuate said device in the manner hereinbefore described in connection with the construction shown in the preceding figures. If, however, the operator should desire to secure a 40 double letter space movement of the carriage to the right, at each depression of the pivoted device 59, it is necessary to depress the key or finger piece 78 at the same time that the 45 pivoted device 59 is depressed, thereby removing the stop 75 from the path of the shoulder 77 so that the relative movement between the stop 58^a and the carriage will be twice the extent of that afforded when 50 the stop 75 is in the obstructing position shown in Fig. 8. When the stop 75 is removed from the path of the shoulder 77 and the pivoted device 59 is depressed to the 55 operative position shown in Fig. 7, pressure exerted upon the carriage from left to right will force the carriage independently of the stop device 58^a and its coöoperating rack a distance corresponding to two letter spaces and the stop 75 will be moved with the carriage beyond the shoulder 77, as shown in Fig. 7. This double letter space movement given to the carriage will cause the feed rack 60 to move a distance corresponding to two of its teeth and the loose dog will reengage

behind the second tooth after the movement 65 has been effected and will hold the carriage against the tension of its spring in the position to which it has been moved.

From the foregoing description it will be understood that the stop device or pawl 58^a (or 58^b) and the rack 56, which may likewise be regarded as a step-by-step device, constitutes means independent of the escapement mechanism of the machine for limiting the backward or retractive movement of 70 the carriage when a backward pressure is applied thereto for affording a predetermined extent of backward spacing movement of the carriage for each actuation of 75 said stop device that said stop devices are 80 normally out of coöperative relation and do not interfere with the movement of the carriage in either direction nor do they affect the escapement mechanism of the machine but they may be brought into coöperation 85 at any point in the travel of the carriage and that the pin and slot connection between the pawl 58 (or 58^a) and the key or pivoted device 59 which carries it constitutes a lost motion connection between the stop and its 90 carrier which affords a step-by-step backward movement of the carriage.

What I claim as new and desire to secure by Letters Patent, is:

1. In a typewriting machine, the combination of a carriage, feed devices for affording a step-by-step feed of the carriage from right to left, and stop devices inoperative to move the carriage but effective for limiting step-by-step retractive movements thereof 100 when said stop devices are brought into engagement and a backward pressure is then applied to the carriage, said stop devices being coöperative at any point in the travel of the carriage.

2. In a typewriting machine, the combination of a carriage, feed devices for affording a step-by-step feed of the carriage from right to left, and stop devices inoperative to move the carriage but effective for limiting step-by-step retractive movements thereof, 110 said stop devices being coöperative at any point in the travel of the carriage and being arranged for engagement before backward pressure is applied to the carriage.

3. In a typewriting machine, the combination of a carriage, escapement mechanism therefor, a key actuated engaging member independent of the escapement mechanism and carried by the carriage, a coöoperating 120 engaging member carried by the frame of the machine, said members being inoperative to move the carriage but adapted to be brought into engagement by an actuation of the key actuated member at any point in the 125 travel of the carriage, and means for affording a predetermined extent of retractive movement of the carriage relative to said en-

gaging members after they are brought into cooperation and by a retractive pressure exerted on the carriage.

4. In a typewriting machine, the combination of a carriage, escapement mechanism therefor, a stop member carried by the carriage, a coöperating stop member carried by the frame of the machine, said stop members being independent of the escapement mechanism and adapted to be brought into cooperative engagement at any point in the travel of the carriage, and a lost motion connection between one of said engaging members and the part that carries it, said lost motion connection affording a retractive movement of the carriage independently of said stop members for a predetermined extent from any point in the travel of the carriage when a retractive pressure is applied to the carriage.

5. In a typewriting machine, the combination of a carriage, escapement mechanism therefor, a stop inoperative to move the carriage, a coöperating rack, said stop and rack being independent of the escapement mechanism, and means for affording a predetermined extent of movement of one of said stop and rack members on its support for the purpose of limiting the retractive movement of the carriage when pressure is separately applied thereto.

6. The combination with the paper carriage of a typewriter, of a platen, a shift rail therefor, a rack connected with the shift rail, a movable stop inoperative to move the carriage, and means for causing the engagement between said stop and rack for the purpose of limiting the retractive movement of the carriage and leaving it in a position one or more letter spaces nearer the beginning of the line than it was before the engagement between the stop and rack and the retraction of the carriage occurred.

7. In a typewriting machine, the combination of a carriage, escapement mechanism therefor, a stop member carried by the carriage and independent of said escapement mechanism, a coöperating stop member carried by the frame of the machine, said stop members being inoperative to move the carriage and normally out of coöperative relation but adapted to be brought into coöperation at any point in the travel of the carriage, means for affording a lost motion between one of said stop members and its support to afford a step-by-step backward feed of the carriage.

8. In a typewriting machine, the combination of a carriage, letter spacing mechanism therefor, and back spacing mechanism independent of said letter spacing mechanism for affording a step-by-step back feed of the carriage, said back-spacing mechanism comprising a stop carried by the carriage, a coöperating stop carried by the frame of the

machine, said stops being inoperative to move the carriage and normally out of coöperative relation but adapted to be brought into coöperation at any point in the travel of the carriage, a lost motion connection between one of said stops and the part that carries it, and a spring for restoring said last mentioned stop to its normal position relatively to the part that carries it.

9. In a typewriting machine, the combination of a carriage, letter spacing mechanism therefor, and back spacing mechanism independent of said letter spacing mechanism for affording a step-by-step back feed of the carriage, said back-spacing mechanism comprising a stop carried by the carriage, a coöperating stop carried by the frame of the machine, one of said stops being in the nature of a rack and the other being in the nature of a pawl, said stops being inoperative to move the carriage and normally out of coöperative relation but adapted to be brought into coöperation at any point in the travel of the carriage, a lost motion connection between one of said stops and the part that carries it, and a spring for restoring said last mentioned stop to its normal position relatively to the part that carries it.

10. In a typewriting machine, the combination of a carriage, letter spacing mechanism therefor, and back spacing mechanism independent of said letter spacing mechanism for affording a step-by-step back feed of the carriage, said back-spacing mechanism comprising a stop carried by the carriage, a coöperating stop carried by the frame of the machine, one of said stops being in the nature of a rack and the other being in the nature of a pawl, said stops being inoperative to move the carriage and normally out of coöperation, a key for bringing said stops into coöperation at any point in the travel of the carriage, and a lost motion connection between one of said stops and the part that carries it.

11. In a typewriting machine, the combination of a carriage, letter spacing mechanism therefor, and back spacing mechanism independent of said letter spacing mechanism for affording a step-by-step back feed of the carriage, said back-spacing mechanism comprising a stop carried by the carriage, a coöperating rack carried by the frame of the machine, and a lost motion connection between said stop and the part that carries it so that the carriage may move independently of said stop.

12. In a typewriting machine, the combination of a carriage, letter spacing mechanism therefor, and back spacing mechanism independent of said letter spacing mechanism for affording a step-by-step back feed of the carriage, said back spacing mechanism comprising a key, a stop carried by said

key, a lost motion connection between said stop and key whereby one may move independently of the other, and a rack with which said stop coöperates to limit the backward movement of the carriage when an engagement is effected between said stop and rack, the extent of lost motion between the stop and key determining the extent of backward movement that may be given to the carriage at each operation.

13. In a typewriting machine, the combination of a carriage, letter spacing mechanism therefor, and back spacing mechanism for affording a step-by-step back feed of the carriage, said back-spacing mechanism comprising a key carried by the carriage, a stop carried by said key, a lost motion connection between said stop and key, a spring tending to maintain a normal relation between said stop and key, and a rack carried by the frame of the machine and with which said stop coöperates to limit the backward movement of the carriage when an engagement is effected between said stop and rack, the extent of lost motion between the stop and key determining the extent of backward movement that may be given to the carriage at each operation.

14. In a typewriting machine, the combination of a carriage; a platen carried thereby, a shift rail for said platen, carriage feed mechanism, and back - spacing mechanism, said back - spacing mechanism comprising a key carried by the carriage, a stop, a lost-motion connection between said stop and key for affording a backward movement of the carriage, and a rack connected with said shift rail and with which the stop is adapted to be brought into coöperation at any point in the travel of the carriage.

15. In a typewriting machine, the combination of a carriage; a platen carried thereby; a shift rail for said platen; carriage feed mechanism; and back spacing mechanism, said back - spacing mechanism comprising a pivoted key carried by the carriage, a stop, a sliding connection between said stop and key for affording a backward movement of the carriage, a spring for restoring the sliding stop to normal position on the pivoted key, and a rack carried by said shift rail and with which the stop is adapted to be brought into coöperation at any point in the travel of the carriage.

16. In a typewriting machine, the combination of a carriage; a platen adapted to be shifted for upper and lower case writing; a shift rail for said platen; carriage feed mechanism; and back - spacing mechanism for affording a step-by-step backward feed of the carriage, said back-spacing mechanism comprising a pivoted spring restored key carried by the carriage, a stop, a sliding connection between said stop and key for affording a backward movement of the

carriage, a spring for restoring the sliding stop to normal position on the pivoted key, and a rack connected with said shift rail and with which the stop is adapted to be brought into coöperation at any point in the travel 70 of the carriage to maintain the stop fixed while the carriage receives a backward movement for a predetermined extent.

17. In a typewriting machine, the combination of a carriage, a stop member carried by the carriage, a coöperating stop member carried by the frame of the machine, said stop members being normally out of coöperative relation and adapted to be brought into coöperation at any point in the travel 75 of the carriage, means for affording a lost motion between one of said stop members and its support to afford a step-by-step backward feed of the carriage, and means for varying the extent of said lost motion. 85

18. In a typewriting machine, the combination of a carriage, a stop member carried by the carriage, a coöperating stop member carried by the frame of the machine, said stop members being normally out of coöperative relation but adapted to be brought into coöperation at any point in the travel 90 of the carriage, means for affording a lost motion between one of said stop members and its support to afford a step - by - step 95 backward feed of the carriage, and hand controlled means for affording different extents of lost motion as may be desired.

19. In a typewriting machine, the combination of a carriage, a stop member carried by the carriage, a coöperating stop member carried by the frame of the machine, said stop members being normally out of coöperative relation but adapted to be brought into coöperation at any point in the travel 100 of the carriage, means for affording a lost motion between one of said stop members and its support to afford a step - by - step single letter space backward feed of the carriage, and hand controlled means for increasing the extent of lost motion at will. 110

20. In a typewriting machine, the combination of a carriage, a stop member carried by the carriage, a coöperating stop member carried by the frame of the machine, 115 said stop members being normally out of coöperative relation but adapted to be brought into coöperation at any point in the travel of the carriage, means for affording a lost motion between one of said stop members and its support to afford a step-by-step single letter space backward feed of the carriage, and spring restored key actuated means for affording an increased extent of lost motion at will. 120

21. In a typewriting machine, the combination of a carriage, a stop member carried by the carriage, a coöperating stop member carried by the frame of the machine, said stop members being normally out of co- 125

operative relation but adapted to be brought into coöperation at any point in the travel of the carriage, means for affording a lost motion between one of said stop members 5 and its support to afford a step-by-step backward feed of the carriage, a movable limiting stop normally in the path of the lost motion stop member, and means for moving said limiting stop out of the path of said lost 10 motion stop member.

22. In a typewriting machine, the combination of a carriage, a stop member carried by the carriage, a coöoperating stop member carried by the frame of the machine, said 15 stop members being normally out of coöperative relation but adapted to be brought into coöperation at any point in the travel of the carriage, means for affording a lost motion between one of said stop members 20 and its support to afford a step-by-step backward feed of the carriage, a pivoted spring restored limiting stop normally in the path of the lost motion stop member, and a key connected to said limiting stop to move it 25 out of the path of the lost motion stop member.

23. In a typewriting machine, the combination of a carriage; letter spacing mechanism therefor; and back spacing mechanism for affording a step-by-step back feed of the carriage, said back-spacing mechanism comprising a stop carried by the carriage, a coöoperating stop carried by the frame of the machine, said stops being normally out of coöperative relation but adapted 30 to be brought into coöperation at any point in the travel of the carriage, a lost motion connection between one of said stops and the part that carries it, a spring for restoring said last mentioned stop to its normal position relatively to the part that carries it, and a hand-controlled movable limiting stop normally in the path of that stop which has a lost-motion connection, whereby 35 the extent of lost motion may be varied.

24. In a typewriting machine, the combination of a carriage; letter spacing mechanism therefor; and back spacing mechanism for affording a step-by-step back feed 40 of the carriage, said back-spacing mechanism comprising a stop carried by the carriage, a coöoperating rack carried by the frame of the machine, a lost motion connection between said stop and the part that carries it, and means for varying the extent of movement afforded by said lost motion connection.

25. In a typewriting machine, the combination of a carriage; letter spacing mechanism therefor; and back spacing mechanism for affording a step-by-step back feed 45 of the carriage, said back spacing mechanism comprising a key, a stop carried by said key, a lost motion connection between

said stop and key, means for varying the extent of lost motion between said stop and key, and a rack with which said stop coöperates to limit the backward movement of the carriage when an engagement is effected between said stop and rack, the extent of lost motion between the stop and key determining the extent of backward movement that may be given to the carriage at each operation.

26. In a typewriting machine, the combination of a carriage; letter spacing mechanism therefor; and back spacing mechanism for affording a step-by-step back feed of the carriage, said back spacing mechanism comprising a key carried by the carriage, a stop carried by said key, a lost motion connection between said stop and key, a spring for restoring the normal relation between said stop and key, means for varying the extent of lost motion between said stop and key, and a rack carried by the frame of the machine and with which said stop coöperates to limit the backward movement of the carriage when an engagement is effected between said stop and rack, the extent of lost motion between the stop and key determining the extent of backward movement that may be given to the carriage at each operation.

27. In a typewriting machine, the combination of a carriage; a platen carried thereby; a shift rail for said platen; carriage feed mechanism; and back-spacing mechanism, said back spacing mechanism comprising a key carried by the carriage, a stop, a lost motion connection between said stop and key for affording a backward movement of the carriage, means for varying the extent of lost motion between said stop and key, and a rack connected with said shift rail and with which the stop is adapted to be brought into coöperation at any point in the travel of the carriage.

28. In a typewriting machine, the combination of a carriage; a platen carried thereby; a shift rail for said platen; carriage feed mechanism; and back spacing mechanism; said back spacing mechanism comprising a pivoted key carried by the carriage, a stop, a sliding connection between said stop and key for affording a backward movement of the carriage, means for varying the extent of lost motion between said stop and key, a spring for restoring the sliding stop to normal position on the pivoted key, and a rack connected with said shift rail, and with which the stop is adapted to be brought into coöperation at any point in the travel of the carriage.

29. In a typewriting machine, the combination of a carriage; a platen adapted to be shifted for upper and lower case writing; a shift rail for said platen; carriage

feed mechanism; and back spacing mechanism for affording a step-by-step backward feed of the carriage, said back spacing mechanism comprising a pivoted spring restored key carried by the carriage, a stop, a sliding connection between said stop and key for affording a backward movement of the carriage, means for varying the extent of lost motion between said stop and key, a spring 10 for restoring the sliding stop to normal position on the pivoted key, and a rack connected with said shift rail and with which the stop is adapted to be brought into co-operation at any point in the travel of the carriage to maintain the stop fixed while the carriage receives a backward movement for a predetermined extent.

30. In a typewriting machine, the combination of a carriage; letter spacing mechanism therefor; and back spacing mechanism for affording a step-by-step backward feed of the carriage; said back spacing mechanism comprising a key, a stop carried by said key, a lost motion connection between said 20 stop and key, a second key carried by said first mentioned key, a regulating stop controlled by said second key and coöperating with said first mentioned stop to limit its movement, and a stop member that coöperates with said first mentioned stop to limit the backward movement of the carriage.

31. In a typewriting machine, the combination of a carriage; letter spacing mechanism therefor; and back spacing mechanism for affording a step-by-step backward feed of the carriage, said back spacing mechanism comprising a key, a stop carried by said key, a lost motion connection between said stop and key, a second key carried by said first 35 mentioned key, a regulating stop controlled by said second key and coöperating with said first mentioned stop to vary the extent of lost motion between said first mentioned stop and its key, and a rack with which said

first mentioned stop coöperates to limit the 45 backward movement of the carriage.

32. In a typewriting machine, the combination of a carriage; and back spacing mechanism therefor; said back spacing mechanism comprising coöperating stop members 50 that are adapted to be brought into co-operation at any point in the travel of the carriage to afford a step-by-step backward movement of one or more letter spaces as may be desired at each actuation, and keys 55 coöperating with said stop members, one of said keys controlling the stop members to afford a single letter step-by-step backward feed of the carriage and the other key being operable to afford a movement of the carriage for a plurality of letter-space distances at each step-by-step feed.

33. In a typewriting machine, the combination of a carriage; and back spacing mechanism therefor, said back spacing mechanism comprising a rack, coöperating stop members, one of said stop members being adapted to be brought into co-operation with the rack at any point in the travel of the carriage to afford a step-by-step backward movement of one or more letter spaces as may be desired at each actuation, and keys 65 coöperating with said stop members, one of said keys controlling the engagement of one of said stop members with the rack to afford 70 a single letter step-by-step backward feed of the carriage and the other key co-acting with the other stop member to afford a movement of the carriage for a plurality of letter 75 space distances at each step-by-step feed.

Signed at the borough of Manhattan, city of New York, in the county of New York, and State of New York, this 17th day of April A. D. 1906.
